HEM GAUGE

Myrle J. Rumpel, Hayward, Calif.

Application April 25, 1952, Serial No. 19,468

Term of patent 14 years

(Cl. D52—1)

To all whom it may concern:

Be it known that I, Myrle J. Rumpel, a citizen of the United States and a resident of the city of Hayward, county of Alameda, State of California, have invented a new, original, and ornamental Design for a Hem Gauge, of which the following is a specification, reference being had to the accompanying drawing, forming part thereof.

Figure 1 is a top perspective view of a hem gauge, showing my new design.

Figure 2 is a bottom perspective view of the hem gauge, shown in Figure 1.

Figure 3 is a side elevational view of the hem gauge, and

Figure 4 is an end elevational view of the same.

I claim:

The ornamental design for a hem gauge, substantially as shown.

MYRLE J. RUMPEL.
